KINJIRO NAKANISHI, OF FUKUOKA, JAPAN

PHOTOELECTRICALLY CONTROLLED PATTERN APPARATUS

Application filed November 5, 1926. Serial No. 146,485

My invention relates to a photoelectrically controlled apparatus for shedding motion in looms for weaving figured fabrics, and is also applicable to machines for cutting figured cards used in jacquard and dobby machines. The invention comprises a photoelectric device controlled by the light projected through the pattern sheet, a circuit including said photoelectric device and a source of current, circuits each including a magnet, a plurality of annularly arranged contacts each connected with respective magnet, and a contact arm adapted to be moved step-by-step in synchronism with the movement of the pattern and adapted to successively engage with said annularly arranged contacts. As the photoelectric device, I prefer to employ a photoelectric cell, selenium cell, photo-Galvanic cell, Thalhoffed cell, or the like. The object of the invention is to provide a photoelectrically controlled system for looms and for card cutting machines, which may be operated effectively in an economical manner.

The accompanying drawings illustrate my invention, in which:—

Figure 1 is a diagrammatic view of the apparatus according to my invention applied to the loom for weaving figured fabric, including the electrical connection,

Figure 2 shows a section of a part of the shedding motion,

Figure 3 is a detail showing in section the light controlled device, in which light is projected to the photoelectric device through the pattern,

Figure 4 is a modified form of the light controlled device in which light is reflected and directed by the pattern sheet to the photoelectric device, and

Figure 5 is a plan view of the insulating disc carrying a plurality of annularly arranged contacts and a contact arm cooperating with said annularly arranged contacts.

According to my invention, arranged opposite to a source of light 1 there is provided a photoelectric device 2. Arranged between the source of light 1 and the photoelectric device 2 is a transparent wall 3 which may be formed into a cylindrical shape or into an endless band or into a flat plate. Said trans-

parent wall 3 carries a pattern sheet 4 which consists of a transparent portion and an opaque portion forming a desired figure, and said wall 3 is rotated step-by-step by a suitable mechanism not shown in the drawings. A lens 5 is inserted between the source of light 1 and the transparent wall 3, and a lens 6 is inserted between the transparent wall 3 and the photoelectric device 2. The source of light 1 is enclosed within a reflector box 7. The aforementioned parts are arranged in such a manner that the light passing through the lens 5 is focussed on the pattern 4 and the transparent wall 3, and that the said projected light is passed through the lens 6 and is focussed on the plate of the photoelectric device 2. On the outer side of the pattern 4, there is provided a window plate 8 in order to guide the light from the lens 5 to the pattern surface.

One pole of the photoelectric device 2 is connected with one pole of the source of current 8, and the other pole of the photoelectric device 2 is connected with one terminal 10 of the amplifier 9. The other pole of the source of current 8 is connected with the other terminal 11 of the amplifier 9.

An insulating plate 13 is provided on the top thereof with a plurality of contacts 12, and in said insulating plate 13 is journaled a shaft 14 which is adapted to be rotated step-by-step in synchronism with the transparent wall 3. The shaft 14 carries secured at its upper end a contact arm 15 which is adapted to successively engage with the contacts 12. Secured to the lower end of the shaft 14 is a slip ring 16 cooperating with the contact brush 18 which is secured to the lower part of the stationary table 17. In the drawings, the insulating plate 13 is shown as composed of a disc, and a plurality of contacts 12 are annularly arranged on the top surface thereof. If desired, the insulating plate may be formed into a cylindrical shape and the contacts 12 may be arranged on the periphery of the same.

With each of the annularly arranged contacts 12 on the insulating disc 13 is connected a respective one of the magnets 19 which are adapted to act upon the hooks of the shedding trans-

motion in the loom or upon the perforating rod in case of the card cutting machines. With the contact brush 18 is connected one pole of the source of current 20, of which the other pole is connected with the terminal 22 of the relay 21. Each magnet 19 is connected in parallel with the conductor leading to the terminal 23 of the relay 21. The relay 21 is connected with the amplifier 9 by means of the terminals 24, 25, 26 and 27, in such a manner that the circuit including the source of current 20 is closed by the closed circuit of the source of current 8.

As the photoelectric device 2 in my invention any cell may be employed such as photoelectric cell, selenium cell, photo-Galvanic cell, Thallofied cell, or the like. As the pattern sheet 4, any film or glass plate may be employed on which is painted or otherwise drawn a desired design. Or if desired a photographed film or glass plate may be employed.

In case of weaving different colored fabrics, the transparent wall 3 may be divided into a number of sections, and a pattern for each respective colored figure may be applied to each section.

The operation of the invention briefly is as follows:— The light from the source 1 is passed through the lens 5 and is focussed on the transparent portion of the pattern 4, and then passing through the lens 6 it is projected upon the plate of the photoelectric device 2, whereupon the current flowing through the circuit of the source of current 8 is intensified by the amplifier 9, and by the action of the relay 21 the circuit of the source of current 20 is closed, energizing that magnet 19 which is included in the circuit leading to the contact 12 at the time engaging with the contact arm 15, thus the hook pertaining to that energized magnet 19 is pulled thereby. On the contrary, when the light from the source 1 is projected to the opaque portion of the pattern 4, the photoelectric device 2 will not be brought into action. Therefore the current flowing through the circuit of the source of current 8 is not enough to actuate the relay 21. Thus, the magnet 19 connected with that contact 12 which is at the time engaged by the contact arm 15 is in the open circuit of the source of current 20, so that the hook pertaining thereto will not be acted upon and will maintain its normal position. In Figure 1, the right hand one of the hooks is shown as pulled by the magnet 19, and other two hooks are shown as maintaining the normal position.

The hooks are pushed back to their original position by any suitable means, such for instance as the spring actuated longitudinally movable rod having tappet pins to engage the hooks, shown in Figure 2.

In the modified form shown in Figure 4, contrary to the arrangement shown in Fig-

ure 2, the light from the source 1' is reflected by the pattern 4' and is directed toward the photoelectric device 2'. In this case, the pattern 4' consists of a light absorbing portion and a light reflecting portion. As the photoelectric device, an annularly shaped device 2' is employed, through the central bore of which is passed the projected light.

As will be seen from the foregoing, according to my invention, the magnets 19 are controlled by the photoelectric device 2, and the pattern on the film or glass plate will be thereby transferred directly to the shedding system of the weaving loom or to the card cutting machine, so that elaborately figured fabrics may be readily woven without necessitating the employment of the pattern cards and, in case of card cutting machines, superior cards may be manufactured, in a simple and economical manner.

What I claim is:

A photoelectrically controlled apparatus for use in looms for weaving figured fabrics and for figured-card cutting machines, comprising a source of light, a photoelectric device, controlled by the light projected through the pattern sheet, a circuit including said photoelectric device, a source of current, an amplifier and a relay, shedding motion hooks, a second circuit including a source of current, said relay, a contact arm arranged to be moved step by step in synchronism with the movement of the pattern, a plurality of electro magnets and contacts with which said contact arm is arranged to successively engage, the said electromagnets being each arranged to pull one of said hooks and means to push the hooks back to their original position.

In testimony whereof I affix my signature.
